CLAIM

The ornamental design for a removable sheet packaging, as shown and described.

DESCRIPTION

FIG. 1 is a perspective view of a removable sheet packaging of the present design in an open configuration and in use; FIG. 2 is a perspective view of the removable sheet packaging in an open configuration;

FIG. 3 is a perspective view of the removable sheet packaging of the present design in a closed configuration;

FIG. 4 is a front view of the removable sheet packaging of the present design in the closed configuration;

FIG. 5 is rear view of the removable sheet packaging of the present design in the closed configuration;

FIG. 6 is a left view of the removable sheet packaging of the present design in the closed configuration;

FIG. 7 is a right view of the removable sheet packaging of the present design in the closed configuration;

FIG. 8 is a top view of the removable sheet packaging of the present design in the closed configuration; and,

FIG. 9 is a bottom view of the removable sheet packaging of the present design in the closed configuration.

The portions of the drawings shown in broken lines represent environmental structure and form no part of the claimed design.
